UNITED STATES PATENT OFFICE.

GEORGE H. ABRAMS, OF BROOKLYN, NEW YORK.

REFRIGERATING APPARATUS.

SPECIFICATION forming part of Letters Patent No. 674,822, dated May 21, 1901.

Application filed June 5, 1896. Serial No. 594,354. (No model.)

To all whom it may concern:

Be it known that I, GEORGE H. ABRAMS, a citizen of the United States, residing in Brooklyn, Kings county, in the State of New York, have invented a certain new and useful Improvement in Refrigerating Apparatus, of which the following is a specification.

The invention applies to all that class of refrigerating-machines which operate by the mechanical compression and subsequent expansion of a gas. I provide a compact and efficient apparatus and also a system employing the same for utilizing a substantial portion of the heat developed by the compression by heating the feed-water for steam-boilers or attaining other useful purposes.

I will describe the invention as carried out with the use of atmospheric air, the same or different air being first compressed to a high tension to render sensible a large quantity of heat, and after a portion of the heat is removed, at such a high temperature as to be useful in the arts, the compressed air is allowed to partially expand and give out power. Then the partially-expanded air is further cooled in effecting a preliminary heating of air and also by ordinary means, and finally is very greatly cooled by a special exposure to air at low temperature. After all this the thoroughly-cooled air is allowed to serve in an engine and give out all the power of which it is capable and also to develop the intense cold required. The power developed in the expansion partially offsets the power consumed in the compression. Other points in this system are made the subjects of separate applications for patent. The present invention applies entirely to the portion of the apparatus in which the heat is taken away from the compressed air prior to its being allowed to act expansively to develop the low temperature required.

There have long been known forms of apparatus which are termed "heat-exchangers," in which the heat contained in a fluid at high temperature is transferred to another fluid received at a low temperature, the fluids being kept separate and so conditioned that either may maintain a pressure much higher than that of the other. It has long been known that by sending the two fluids in opposite directions through such apparatus the

fluid to be cooled shall on entering be brought into intimate relations with the fluid which is to be warmed as the latter is about to leave in nearly its warmest condition, and the fluid to be warmed shall on entering be brought into intimate relations with the fluid which is to be cooled as the latter is about to leave, and is consequently in nearly its coolest condition, the arrangement insuring that nearly all the heat will be transferred from one fluid to the other. My apparatus similarly presents the fluids to each other; but I have introduced important improvements in the construction and arrangement of the apparatus, whereby it is made more compact. It is highly convenient and efficient.

My apparatus provides for giving great elasticity in the pipes to allow for the expansion and contraction of the metal.

The accompanying drawings form a part of this specification and represent what I consider the best means of carrying out the invention.

Figure 1 is a diagrammatic view illustrating in general elevation the heat-exchanger embodying my invention in its connected relation to the compressor and other apparatus. Fig. 2 is a central vertical section through the feed-heating or heat-exchanging portion of the apparatus. Fig. 3 is a horizontal section on the line 3 3 in Fig. 2. Fig. 4 is a vertical section of a portion on the line 4 4 in Fig. 2, parts being removed to disclose the pipe-union or box. The remaining figures show a modification. Fig. 5 is a central vertical section; Fig. 6, a horizontal section on the line 6 6 in Fig. 5, and Fig. 7 is a vertical section on the line 7 7 in Fig. 5.

The drawings show the novel parts with so much of the ordinary parts as will suffice to show their relations thereto.

Similar letters of reference indicate corresponding parts in all the figures where they appear.

Referring to Figs. 1, 2, and 3, A is a rigid casing of cast-iron or other suitable material, in which the temperature is highest, as will presently appear.

B is a tall casting bolted on the casing A and containing in its base a chamber B' and having also an upper extended chamber B², in which the heated air is still further cooled

75

90

100

after its partial cooling in the hot chamber below. The entire casting B is cylindrical and adapted to endure a high pressure. It is traversed by two partitions, which may be 5 plane. They inclose between them the chamber B³, which is filled with asbestos or other good non-conductor of heat. The chambers B', B², and B⁴ carry air at a high pressure, which is circulated actively in the direction 10 opposite to the general direction of that in the inclosed pipes, which will be described farther on. The chambers B' and B² are directly connected and are subjected to a flow of air entering first at the chamber B', being transferred 15 directly from one end of this chamber into the chamber B². The air, highly heated by the compressor, is received through the pipe C into the chamber A, where it is partially cooled, giving very nearly its own temperature 20 to the previously-warmed air, which fills this chamber, as will presently appear. The pipe C is convoluted, so as to present a great surface within the chamber A, properly conditioned to allow expansion and contraction 25 with changes of temperature. I prefer that the air thus circulated through the pipe C shall be in the condition of that set forth in the application for patent by me filed May 15, 1896, Serial No. 591,641. Such air having 30 been intensely compressed and raised to an unusually high heat is first usefully deprived of a portion of the same and is then expanded against the opposite face of the compressor-piston to assist the compressing action of the 35 same and is subsequently recompressed to a less degree and led away for utilization by expansion. The compressed hot air after its passage through the pipe C is again returned by way of the apparatus shown in my said application, Serial No. 591,641, for an air-compressor to the apparatus at a later stage through the pipe D, which delivers it into the chamber B'. Here it is cooled by the presence of a great 40 number of convoluted pipes, to be described 45 farther on. After circulating through this chamber B' the partially-cooled air rises through the tall chamber B², which occupies nearly one-half of the cylindrical casting B and there having imparted more of its heat 50 to a further system of pipes at a lower temperature, to be presently described, flows out through a pipe D'. This air still at substantially the same high pressure flows through the ordinary system of pipes (not shown) 55 showered with water in the ordinary manner and universally known as the "condenser." Here the main portion of the remaining heat in the compressed air is removed and carried away with the water. Lastly, before such 60 air is allowed to expand and produce cold it is brought from the condenser through the pipe E and introduced into the lower portion of the tall chamber B⁴. Here it circulates in contact with pipes which are at a low temperature, and it is correspondingly cooled to or 65 below the ordinary temperature. It flows out thus cooled, but still retaining its high pres-

sure, through the pipe E' and goes to the engine, (not shown,) where it is expanded and develops the cold required.

The pipes which convey through the several chambers the fluid which is to be heated are peculiarly adapted to present much surface to receive the heat from the air outside and impart it to the fluid inside to maintain 70 strength, and especially to provide liberally for expansion and contraction due to changes of the temperature. I can use any fluid to be thus heated and utilized. Under ordinary conditions such may be assumed to be either 75 air or water. I will generally refer to it as 80 water. The water is admitted at any temperature which is available—I will assume it to be at or near 100° Fahrenheit—through the pipe M. Within the chamber B² the 85 stream is divided and carried through two pipes M' and M², each formed as shown, in equally-spaced convolutions M⁴ and set so that the horizontal convolutions of one pipe M' shall lie between the corresponding convolutions of the other pipe M². Near the 90 bottom of the chamber B² these pipes are united in a single box M³. A number of pipes N, bent as shown, traverse the chamber B'. The upper end of each is connected 95 to the box M³. The lower end of each delivers into the chamber A. The water descending through this system of pipes becomes heated nearly to the required temperature by the tolerably high temperature of the 100 air in the chambers B² and B'. On entering 105 and circulating within the chamber A it is brought into contact with the intensely-heated pipe C before described, and here it attains its final temperature, the high temperature at which it is ultimately discharged 110 through the pipe O, and may be utilized for feeding boilers, treating goods in dyeing establishments, or for any other useful purposes in which large quantities of highly-heated water are required. It will be understood that if the high temperature in this 115 final chamber A is sufficient to generate steam of considerable pressure it is necessary to pump or otherwise force in the water through 120 the pipe M with a somewhat greater pressure, so that the water will descend through the system of pipes notwithstanding the pressure of the steam in the chamber A. The water will be discharged through the pipe O 125 with a pressure which may be utilized in driving or aiding to drive the pump.

I have previously described in part what takes place in the chamber B⁴, which is maintained at a much lower temperature than the 130 chambers B' and B², the heat being prevented from traversing across by the presence of two partitions and the sufficient intermediate packing of non-conducting material. I will now describe such chamber B⁴ and its work 135 more fully.

T is a pipe which extends up and down several times in the chamber B⁴ and effects the cooling of the air which traverses in the

spaces between such pipes immediately before its passage to the engine, in which it is allowed to expand and produce both power to aid the compressor and intense cold for the

5 manufacture of ice or for other useful purposes. The pipe E admits compressed air to chamber B⁴ where it is subjected to the expanded air return from the refrigerating apparatus or other suitable source through the 10 pipe T, the connections not being shown. If the refrigerating apparatus is worked in any ordinary manner the air delivered into it at a very low temperature—say, at or below zero of the Fahrenheit scale—returns at a considerably-increased temperature by reason of the caloric which it has abstracted from the water in changing it to ice or from the meat in cooling a cold-storage apartment, but its 15 temperature is still far below the ordinary. Assuming that the air is thus received on its return from the refrigerating apparatus at 20 32° Fahrenheit, its traverse through the pipe T will hold the surface of the latter at a temperature only a little above that point. The 25 effect on the compressed air circulated through the chamber B⁴ in contact with such pipe is to lower the temperature of said compressed air down to considerably below that of the ordinary atmosphere. This cooling 30 greatly promotes the cold-producing effect of the expansion of such air, which immediately follows.

Modifications may be made without departing from the principle or sacrificing the 35 advantages of the invention. The number of the convolutions M⁴ in the several pipes and the numbers of the pipes may be increased or reduced. Boiler-iron or other forms of wrought metal may be used for the whole or 40 a portion of the casings A and B. The apparatus instead of being upright may be inverted, or it may be horizontal or variously inclined.

It will be understood that, as already stated, 45 the fluid to be heated may be changed. I attach particular importance to the practicability of sending air instead of water in through the pipe M and allowing air instead of water to be delivered in a heated condition 50 through the pipe O. The selection of one fluid for heating instead of another may vary according as a demand may exist under the particular circumstances in which the apparatus is worked. If there is a use for water 55 and not for air or for air or other elastic fluid in place of water, either may be passed down through the system of pipes M' M².

In case water is used, as first described, and the conditions are such as to generate steam 60 in the chamber A it is important to know about at what depth the water-surface in the chamber stands.

A' is a glass gage-tube connected at the top and bottom and adapted to make the level of 65 the water plainly visible. I propose to use other ordinary appliances, as non-conducting clothing, around any portion or the entire ap-

paratus to restrain the radiation of heat and to use light check-valves at any required points in the system to prevent a backflow 70 under any conditions.

In the modification shown in Figs. 5 to 7, inclusive, is disclosed a construction wherein the tall casting B⁸ embodies only provisions for heating feed-water. In this modification 75 the water after rising in the vertical series of bends M⁸ flows across through an aperture in the partition B⁸ thence passes downward through a pipe T⁸, located in the chamber B⁸, thus affording a compact arrangement for the 80 return of the heated water without exposing it to loss of heat, after which it flows through the coil in the chamber B⁸, and finally discharges into the base-chamber of the apparatus. A⁸ shows a vent for any excess of 85 pressure in the chamber A⁸. It may be constructed in all respects like an ordinary safety valve.

Parts designated by letters in the modifications and not referred to in the specification 90 are similar to correspondingly-marked parts in Figs. 1 to 4, inclusive.

I claim as my invention—

1. The combination with a primary chamber A inclosing a coil C through which highly-heated compressed air is circulated, of a second chamber containing a condenser-pipe T, non-conducting wall B⁸ dividing such chamber into two parts or subchambers B², B⁴, and a coil for carrying the fluid to be heated inclosed in one compartment of such second chamber and delivering it to the primary chamber and a connection with said compartment for admitting the compressed air to surround such coil and be further cooled after it 100 has been previously treated in the primary chamber, a condenser and connections for leading the compressed air to the same and returning it therefrom to another compartment of the second chamber and a coil T in the 105 last-named compartment containing cold expanded air returning from use, said chambers being arranged in close relation and together with the coils, &c., embodied in a single composite structure for utilizing the heat of compression in the air, substantially as herein 110 specified.

2. The combination with a primary chamber A inclosing a coil C through which highly-heated compressed air is circulated, of a second chamber containing a condenser-pipe T, non-conducting wall B⁸ dividing such chamber into two parts or subchambers B², B⁴, and a pair of pipes having the interlocking horizontal bends or convolutions M⁴ for conveying the fluid to be heated and for delivering it to the primary chamber, and a connection with the second chamber for admitting the compressed air thereto but at a lower temperature to circulate externally to said pipe 120 bends or convolutions, said chambers being arranged in close relation and together with the coils, convolutions, &c., being embodied in a single composite structure for utilizing 125 130

the heat of compression in the air, substantially as herein specified.

3. The combination with the condenser-engine and refrigerating-room, of a primary chamber A inclosing a coil C, through which highly-heated compressed air is circulated, a second chamber divided by a non-heat-conducting partition into two compartments, a coil in one compartment for conveying the fluid to be heated and for delivering it to the primary chamber, a connection with said compartment for admitting compressed air thereto but at a lower temperature to circulate externally in contact with the coil therein, return air-pipe from the refrigerating-room in said second compartment, connections for circulating the compressed gas about said pipe on its way to the engine, and induction and ejection openings in the latter for the circulation of the air after it leaves the other compartment, the chamber and compartments being arranged in close relation and together with the coils, condensing-pipe T, connections, &c., being embodied in a single composite structure for utilizing the heat of compression, substantially as herein specified.
4. The combination with a primary chamber A inclosing a coil C through which highly-heated compressed air is circulated, a second chamber mounted thereon and divided by a non-heat-conducting partition into two compartments, one of which contains a pair of pipes having the interlocking horizontal bends or convolutions M⁴ for conveying the fluid to be heated and for delivering it to the primary chamber, a condensing-pipe in the second compartment, air induction and ejection openings in the latter and a connection with the first-mentioned compartment for admitting the compressed air thereto, but at a lower temperature than when admitted directly to chamber A, to circulate externally in contact with the coil therein, together with a condenser interposed in the compressed-air circuit between the two compartments, substantially as herein specified.

5. The combination with the chamber A having a pipe arranged in bends therein, and with its ends extending externally to receive

and retain the heated air of compression, of the chamber B' arranged on chamber A and having connections for the passage of the compressed air at a lower temperature, a pipe M in the chamber B for circulating the fluid to be heated, said pipe having the horizontal interlocking convolutions and continued by a pipe within the chamber B', discharging into the chamber A, substantially as herein specified.

6. In a system for utilizing the heat of compression in compressed air, the combination with a chamber A, having a pipe in bends therein for circulating the heated air of compression, of a compressor communicating with said pipe from both sides of its piston, an upper chamber B containing a pipe for containing liquid to be heated, communicating with the chamber, a pipe D establishing communication between the compressor-discharge and the chamber B, and a suitable outlet for the latter, substantially as herein specified.

7. In a system for utilizing the heat of compression in compressed air, the combination with a condensing-engine and refrigerating-room, of a chamber A having a pipe in bends therein for circulating the heated air of compression, a compressor communicating with said pipe from both sides of its piston, an upper chamber B, divided by a non-conducting partition into two compartments, a convoluted pipe in the first and discharging into chamber A, a return air-pipe from the refrigerating-room in the other compartment, connections for circulating the compressed gas about said pipe on its way to the engine, a pipe D establishing communication between the compressor-discharge and the first compartment, and connections for conveying the compressed air from the latter to and through the second compartment, substantially as herein specified.

In testimony that I claim the invention above set forth I affix my signature in presence of two witnesses.

GEORGE H. ABRAMS.
